UNITED STATES PATENT OFFICE.

NICHOLAS THOMAS, OF BURLINGTON, WISCONSIN.

PANORAMIC CAMERA.

SPECIFICATION forming part of Letters Patent No. 645,276, dated March 13, 1900.

Application filed July 15, 1899. Serial No. 723,968. (No model.)

To all whom it may concern:

Be it known that I, NICHOLAS THOMAS, a citizen of the United States, residing at Burlington, in the county of Racine and State of Wisconsin, have invented certain new and useful Improvements in Panoramic Cameras; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to panoramic cameras, and has for its object to construct such a camera in which the lens will revolve around a center and a film-carrier will travel in the same direction, but at a different speed; also, to provide a construction in which the lens and the film are supported by the same carrier, so as to move together.

It has, further, for its object to provide improved features of construction and arrangement of parts, as will be made to hereinafter appear.

To the accomplishment of the foregoing and such other objects as may hereinafter appear the invention consists in the construction and also in the combination of parts hereinafter particularly described, and then sought to be specifically defined by the claims, reference being had to the accompanying drawings, forming a part hereof, and in which—

Figure 1 is a front elevation of the camera looking in the direction of the lens. Fig. 2 is a vertical section through the same. Fig. 3 is a plan view with parts in horizontal section and with a part of the top broken away. Fig. 4 is a horizontal section through the casing or shell containing the gear-operating mechanism, said mechanism being shown in full lines. Fig. 5 is a detail view of the rack-gear, and Fig. 6 is a sectional detail view of the speed-regulating device.

In the drawings the numeral 1 designates the camera-case, which may be of any desired form, but which is rotatable around a center and which carries a lens-holder 2, which may be of any approved pattern, but which in this instance is provided at one end with flanges 3, adapted to slide beneath the plate

4, so that it can be readily detached from the case 1 when desired. The case 1 is provided with a slot 5 for the passage of the rays of light from the lens-holder, at which point is also provided a shutter 6, provided with an opening 7, which when in register with the slot 5 will permit the light-rays to enter the case 1 and act upon the sensitive film, said shutter being provided with a thumb-piece 8, by which it may be moved so as to bring the solid portion of the shutter opposite the slot 5, and thus cut off the light-rays from the interior of the case. The case 1 also carries a film-holder 9, which is provided with a sliding section 10 to permit the insertion and withdrawal of the roll or film 11, which is wound around a core 12, which will be suitably journaled in the film-holder, so as to rotate.

Inside of the casing 1 is a rotatable cylinder 13, designed to receive the film 11 as supplied from its roll, and to which the light-rays are transmitted as the cylinder passes in front of the lens-holder. The film 11 may be attached to the cylinder 13 in any suitable manner, but I prefer to attach it as shown—that is, by passing it through a slot 14 in the cylinder and securing it then to a suitable fastening device 15 on the inside of the cylinder.

The casing 1 and cylinder 13 are sustained in their proper position by a shaft 16, which may be stationary and may be held in place by a nut 17 at one end, the other end being formed with a head 18, which may bear against a suitable frame 19, secured inside of a box or casing 20, said frame 19 having a hub 21, through which the shaft 16 will pass; but these details may be varied and are not an essential part of the invention. Encircling the shaft 16 is a sleeve or hollow shaft 22, which has secured to it by screws 23 or otherwise a pinion 24, and to which sleeve the cylinder 13 is secured in any suitable manner so as to turn therewith. One manner of securing the cylinder to the sleeve or hollow shaft may be by means of the hubs 25 and 26 of the cylinder, which may be secured to the sleeve by keys or screws or in any other well-known manner. The upper hub 26 forms a part of a spider 27, the flange 28 of which is secured to the inside of the cylinder, a space

being left between the periphery of the cylinder 13 and the inner wall of the case 1 for the film, which is wound around the periphery of the cylinder after the impression is made 5 on the film by the light-rays from the lens-holder. A flange 29, projecting from the top of the case 1, fits inside of the cylinder, as shown in Fig. 2, so as to make a light-tight joint. The top of the case 1 has hinged doors 10 30, through which access may be had to the interior of the case and also of the inside cylinder for the placing of the removable lens-holder for transportation and also of extra rolls of film.

15 The outside case carrying the lens is rotatable around a center by suitable means, so that a picture may be taken of all objects within the range of rotation of the lens, and the film-receiving drum or cylinder is caused 20 to travel around a center at the same time that the lens is caused to travel and at a faster speed than the lens, so that a fresh surface of film is constantly presented to the light-rays, the film being wound upon its receiving-drum 25 as it is unwound from the film-carrying roll. Suitable mechanism is provided for moving the film-receiving drum at a faster speed than the lens-carrying case. The means which I find specially well adapted for rotating the 30 lens-case and film-receiving drum is a pinion 31, connected by screws 32 or otherwise to the case 1, and a smaller pinion 24, connected to the film-receiving drum 13, for instance, by securing it to the shaft 22 of the drum by 35 screws 23 or otherwise, and a suitable rack 35 for imparting a rotary motion to said pinions, such a rack being illustrated as of segmental form and having one set of teeth 36 to engage the teeth of the pinion 31 and another set of teeth 37 to engage the smaller pinion 24, so that as the rack is moved rotary motion 40 is transmitted to the case and the film-receiving drum through their respective pinions, and the film-receiving drum is caused 45 to travel faster than the lens-carrying case, thus presenting a fresh surface of film to the light-rays as the two parts travel around their center. By having the lens-carrying case and the film-receiving drum travel in the same 50 direction and at different speeds from each other a sharper and clearer picture is obtained of the changing views. The rack 35 is shown as connected to a shaft 38 and may be operated by any suitable clock mechanism or 55 otherwise, the particular means illustrated in the drawings consisting of a spring 39, connected to the shaft so as to move the rack in a direction to rotate the camera-case and film-receiving drum. The end of the shaft 38 is 60 provided with suitable means—for instance, with a thumb-nut 40—by which the camera-case and film-receiving drum may be moved backward.

In order that the film may not be unwound 65 from its receiving-drum when rotated backward, a suitable clutch is employed which

will cause the film-receiving drum to be positively driven in the direction to wind the film thereon and permit it to be moved in the opposite direction without unwinding the film. 70 A suitable clutch for this purpose consists, as illustrated, of a ratchet 41, secured to the shaft 22 of the drum 13, and one or more pawls 42, pivoted to a suitable part of the drum 13 and which may be under the influence of a spring 43, so that when the shaft 22 is driven in one direction the parts of the clutch will engage so as to drive the drum, so as to wind the film thereon, and when the camera-case is turned backward the parts will slip 80 over the ratchet and permit the film-drum to be drawn backward with the camera-case by the pulling action of the film, the mounting of the film-drum on its shaft being so free that the drum can be turned back without sufficient friction to unwind the film from either its roll or from off the drum.

Suitable means are employed for regulating or governing the speed of the camera-case and film-receiving drum. For such purpose 90 I have illustrated a piston-cylinder 44, pivotally connected at one end by its shaft or trunnions 45 to the frame 19, as illustrated in Figs. 4 and 6, and provided with a piston or plunger 46, which at its outer end is hinged 95 or pivotally connected to an arm or crank 47, extending from the hub of the rack 35, supported and carried by the shaft 38. The cylinder 44 is provided with a port 48, controlled by a tapering plug or valve 49, so as to regulate the quantity of air or cushioning agent that may pass through the same in the operation of the plunger or piston, and thus govern the speed of the rack and through it the rotation of the camera-case and film-drum. 100 By adjusting the tapering valve the size of the port can be increased or diminished. I have also shown a longitudinal port 50 in the piston or plunger, which has a spring-influenced valve 51 at its inner end and which in 110 the outward movement of the plunger or piston will open the longitudinal port, but in the inward movement will close the port. Any other suitable speed regulating or governing device may be used. 115

On the top of the camera-case is a level 52. It is of course understood that the parts will be so proportioned and adjusted that the proper relative speed will be given to the camera-case carrying the lens and the film-receiving drum, so that the film-drum will travel at the speed required to expose the fresh film to the light-rays as the view changes. For instance, if the film-receiving drum is of the diameter that would be described by a 125 radius equal to the focus of the lens the film should travel about twice as fast as the lens; but if the diameter be equal to the focus then it should travel about three times as fast as the lens-carrier. It will also be understood 130 that there will be employed any suitable means for controlling the length of the pic-

ture taken; but the invention is not in such means, and as any preferred means may be employed for the purpose none need be illustrated.

As before stated, the camera-case which carries the lens and the film-drum which receives and carries forward the film may both be moved backward by simply turning the camera-case backward by grasping the lens-tube with the hand, which movement will also move backward the film-carrier. Means may be provided for locking the camera-case and film-receiving drum together when they are to be moved backward, or some suitable frictional device may be employed for preventing the film-core 12 from turning to unwind the film when the film-carrier and lens-carrier are moved backward; but such means are not illustrated, as the same are not claimed herein and are not essential to the other features of the invention.

I have illustrated and described with particularity the details of construction and arrangement of parts adapted for the successful operation of a camera of the kind described; but my invention is not confined to such details except where they are particularly specified in the claims, and it is obvious that various changes may be made without departing from the essential features of my invention.

Having described my invention and set forth its merits, what I claim is—

1. In a panoramic camera, the combination with a revolving lens-carrier and film-holder, of a revolving film-receiving drum, said lens-carrier and drum turning in the same direction and at different speeds, substantially as described.

2. In a panoramic camera, the combination with a revolving lens-carrier and film-holder, of an internal film-receiving drum revolvable at a greater speed than the lens-carrier and

traveling in the same direction therewith, substantially as described.

45

3. In a panoramic camera, the combination with a revolving camera-case carrying a lens-holder and a film-holder in its rotation, of a film-receiving drum rotatable in the same direction with the camera-case and at a different speed therefrom, substantially as described.

50

4. In a panoramic camera, the combination with a revolving lens-carrier and film-holder, of a revolving film-receiving drum adapted to travel in the same direction and at a different speed from the lens-carrier, and a governor for regulating the speed, substantially as described.

55

5. In a panoramic camera, the combination of the revolving camera-case carrying a lens-holder and a film-holder, a revolving film-receiving drum, pinions of different diameters connected one with the camera-case and the other with the film-receiving drum, means for operating said pinions to cause the camera-case and film-receiving drum to travel in the same direction and at different speeds, clutch mechanism whereby the film-drum is driven positively in one direction and permitted to turn backward without unwinding the film therefrom, and means for regulating the speed of rotation of the parts, substantially as described.

60

6. In a panoramic camera, the combination with a revolving lens-carrier, of a film-carrier, and means for moving the film in the same direction as the lens and at a faster speed than the lens-carrier, substantially as described.

65

In testimony whereof I affix my signature in presence of two witnesses.

NICHOLAS THOMAS.
